UNITED STATES PATENT OFFICE

MAX ADLER, OF SAN DIEGO, CALIFORNIA

COMBINATION BED AND CHAIR

Application filed January 15, 1930. Serial No. 420,890.

My invention relates to combination beds and chairs, and the objects of my invention are: First, to provide an article of furniture of this class which closely resembles a conventional chair when folded; second, to provide a bed-chair in which the various folding portions thereof readily interlock so as to form a strong, sturdy chair capable of 55 withstanding the wear of the conventional chair; third, to provide a bed-chair which need not be more bulky or cumbersome when folded than the conventional overstuffed chair; fourth, to provide a bed-chair which readily lends itself to various styles and designs of furniture so as to harmonize with other furnishings of a room; fifth, to provide a bed-chair which may be converted from a chair to a bed or from a bed to a chair with minimum time and effort; sixth, to provide a bed-chair which provides storage space for 60 all or part of the bed covers therefor; seventh, to provide a bed-chair which forms a full length bed when unfolded, having no cross portions positioned so as to reduce comfort; eighth, to provide a bed-chair which may be 65 readily constructed as a single or double bed; ninth, to provide a bed-chair in which the locking means for holding it in its folding position may be readily concealed; and tenth, to provide on a whole a novelly constructed 70 bed-chair which is extremely simple of construction, proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon, which form a part of this application, in which:

Figure 1 is a side elevational view of my bed-chair when in its folded position; Fig. 2 is a fragmentary, front elevational view thereof, also in folded position; Fig. 3 is a rear elevational view thereof; Fig. 4 is a 80 side elevational view thereof, when in its ex-

tended position forming a bed; Fig. 5 is a fragmentary, sectional view through 5-5 of Fig. 3, with parts and portions shown in elevation to facilitate the illustration; Fig. 6 is a fragmentary, sectional view substantially 55 through 6-6 of Fig. 2; and Fig. 7 is an enlarged, fragmentary, sectional view through 7-7 of Fig. 6, with the padding or upholstering shown by dotted outlines.

Similar characters of reference refer to 60 similar parts and portions throughout the several views of the drawings.

Base member 1, feet 2, seat frame 3, back frame 4, central bed cushion 5, foot bed cushion 6, head bed cushion 7, cover flap 8, retaining catches 9, back frame supporting legs 10, cables 11, springs 12, guides 13 and 14, anchors 15, catch lever supporting plates 16, catch levers 17, journal pins 18, fittings 19, 70 catch pins 20, catch lever actuating cable 21, catch lever springs 22, guides 23, and handle 24 constitute the principal parts and portions of my bed-chair.

The base member is substantially box-shaped, comprising four substantially vertically extending walls surrounding a bottom portion. The base member 1 is supported at its lower corners on feet 2. The base member is mounted with its open end at the upper 75 side.

Hinged to the forward upper side of the base member 1 is a seat frame 3, which is adapted to rotate from superposed position relative to the base frame, as indicated by 80 Figs. 1 and 2, to a horizontally disposed position, as shown in Fig. 4. The hinges 3a which connect the seat 2 with the base member 1 are mounted adjacent the side margins of the base member and seat frame. The forward side 1a of the base member 1 is cut away between the hinges, as shown best by dotted lines in Fig. 2, so that no partition at this point can render the chair, when used as a bed, uncomfortable. Hinged to the rear 85 side of the base member 1 in a manner similar to the seat frame 3, is a back frame 4. At the back also the base member 1 is cut away between the hinges as indicated by 1b so that a partition is eliminated at this point.

Positioned in the base member 1, so as to

normally extend slightly above the upper margins of said base member, is a central bed cushion 5. The central cushion 5 may be spaced up from the bottom of the base 1, as indicated by 1c in Fig. 4, so that pillows or bed covering may be positioned therein. If this is done, the base of the central cushion is made stiff enough to support its own weight, and the weight of an occupant.

10 The forward side of the central bed cushion is attached to a removable foot bed cushion 6, which fits in a relatively shallow receptacle portion 3b. The bottom of the receptacle portion 3b may be a web of suitable cloth so as to be relatively flexible, yet capable of supporting an occupant. A seat cushion 3c is supported on the opposite side of the partition from the foot cushion 6. When the device is used as a chair, the seat cushion 3c is uppermost, as shown in Figs. 1 and 2; and when used as a bed, the foot cushion 6 is uppermost, as shown in Fig. 4.

25 When the seat frame 3 is open to the position shown in Fig. 4, it rests upon the normally upper sides of the arm rests 3d, or upon a suitable protecting knob 3e extending therefrom.

30 Suitable upholstery cloth 4b of sufficient strength extends between the side members 4c of the back frame 4. The back frames are held in spaced relation to each other by suitable cross members 4d. The connecting or back portion 4b of upholstery cloth extends downwardly and covers the rear sides of the base member 1, as shown best in Figs. 1, 3, and 4.

40 Positioned upon the back portion 4b is a head bed cushion 7 which is joined to the rear side of the central bed cushion 5 by a web portion. The head bed cushion 7 is covered by a suitable flap 8 when the device is used as a chair, as shown in Fig. 1. The flap 8 is permanently secured at its normally upper margin, and it is removably secured at its normally lower corners to suitable hooks or receiving hinges 9 secured to the normally lower corners of the side frames 4c, as shown by dotted lines in Fig. 4.

50 The side frames 4c are preferably made double, forming spaces or recesses 4e therebetween, which extend for approximately half the length of the back member from the normally upper ends downwardly. Each space 4e is open at its outer side and is adapted to receive a leg member 10, which is pivotally mounted at its upper end between the side walls of the corresponding side members 4c as shown best in Fig. 4. Each leg 10 is adapted to be shifted about its pivotal axis from its concealed position within the recess or slot 4e, as shown in Figs. 3 and 6 to the extended position shown in Fig. 4, in which position it supports the normally upper end of the chair back from the floor.

65 Each leg 10 has secured thereto a cable

11, which is connected to the normally upper end of the leg and remains within the slot 4e at all times. Each cable 11 extends longitudinally with the side members 4c towards the normally low end of the back frame 4. Somewhere in its length each cable 11 is provided with a spring 12. The cable may extend through a suitable tubular guide 13 positioned in the recess 4e inwardly from the corresponding leg 10.

70 Each cable 11 also passes over a guide block 14 positioned at the lower end of the back frame 4. Each cable 11 is guided by the corresponding guide block 14 approximately through the center of rotation of the back frame, and into the base member 1, where it is secured to a suitable anchor 15. When the back member is rotated from the position shown in Fig. 1 to the position shown in Fig. 4, the cables 11 tend to pull the legs 10 to their extended position shown in Fig. 4. In order to maintain the legs within the recesses 4e, suitable friction catches 10b may be set in the leg members 10, as shown in Figs. 6 and 7.

75 The normally upper portions of the outer members of the side frames 4c are provided with extended portions 4f. When the device is used as a chair, as shown in Fig. 1, the extended portions 4f project forwardly into overlapped relation with the upper rear margins of the arm rest portions 3d of the seat frame 3.

80 As shown best in Fig. 1, the rear side of the base member 1, and normally rear side of the seat frame 3 and back frame 4 slant rearwardly as well as upwardly. Also, it will be noted that the sides of the seat frame 3 are shorter than the corresponding sides of the base member 1, leaving a narrow space which is filled by the lower portions of the side frames 4c. The normally lower forward portions of the side members 4c thus abut and fit snugly against the normally rear sides of the seat frame 3. The normally lower face 4g of the extension 4f fits snugly against the upper rear margins of the arm rest 3d. Thus, the seat 3 fits firmly against the base 1 when the back frame 4 is in its upper position. When in this position, the cushions 5 and 6 are compressed.

85 Mounted in a recess 4b, formed in the inner side adjacent the normally lower face 4g of the extension 4f are catch lever supporting plates 16, one for each extension.

90 Pivotedly mounted against the normally forward corner of each plate 16, by means of a journal pin 18, is a catch lever 17. One arm 17a of each catch lever 17 extends downwardly through the normally lower end of the corresponding extension 4f into a recess 3f formed in the upper side of the corresponding arm rest 3d.

95 This recess 3f may be bordered by a suitable fitting 19, as shown in Fig. 6. Extend-

ing horizontally between the side walls of the recess 3f or between the side walls of the fitting 19, is a catch pin 20 which is adapted to engage on its under side by a hook portion 17b formed by extending the lower end of the arms 17a forwardly, as shown best in Fig. 6.

A second arm 17c extends rearwardly of the point of support of the catch lever within the margins of the extension 4f. This 10 arm 17b extends into the space 4e formed between the pairs of side members 4c, and is connected to a cable 21. A third arm 17b extends upwardly and rearwardly into the extension 4f, and connects at its extended end 15 with the one end of a spring 22, the other end of which is secured to a lug 16a formed by pressing outwardly a portion of the plate 16. The spring 22 tends to depress the normally rear portion of the lever 17 so as to rotate the catch portion 17b of the arm 17a forwardly into engaging relation with the catch pin 20.

The cables 21 from each catch lever 17 may extend through suitable guides 23, upwardly 25 along the spaces 4e behind the leg members. At the upper corner portion of the back member the cables turn inwardly toward the centrally normal upper portion of the back frame 4, and adjacent the central portion pass 30 outwardly and join a suitable handle 24.

The handle 24 may be formed by covering the wire with suitable upholstery cloth, as shown in Fig. 5. The cables may be secured at the central portion 24a of the handle 24. 35 The remaining or extended portion 24b of the handle may be compressed longitudinally by folds of the material so that when the cables are pulled, the extended portions 24b tend to press against the openings in the back 40 member 4, through which the cables pass and always maintain a neat appearing joint.

The chair is formed into a bed by pulling on the handle 24. This first releases the catches 17 from the catch pins 20; continued 45 rotation of the back member around the hinges 4a causes the springs 12 to exert a pressure which overcomes the resistance of the catches 10b whereupon the legs 10 flap out of the openings 4e into the proper position 50 for supporting the back member when using it as a portion of the bed. The flap 8 is then unhooked and thrown over the rear end of the frame 4, as shown in Fig. 4, and the seat frame 3 is rotated from the position 55 shown in Fig. 1 to the position shown in Fig. 4.

The cushion 5 and cushion 6 may readily be lifted up so that the covers packed in the space 1c may be spread upon the bed now 60 formed.

By making the chair of double width a double bed may be formed thereby.

Though I have shown and described a particular construction, combination and arrangement of parts and portions, I do not

wish to be limited to this particular construction, combination and arrangement of parts and portions, but desire to include in the scope of my invention the construction, combination and arrangement substantially 70 as set forth in the appended claims.

Having thus described my invention, what I claim as new and desire to secure by Letters Patent is:

1. In a combination bed and chair, a base member, a seat member hinged to the forward side thereof and shiftable about its pivotal axis from a superposed position with respect to the base member to one side thereof, a back member hinged to the base member at the rear side thereof and shiftable about its pivotal axis from a back supporting position to a horizontal position with respect to the base member, the seat member having at its normally under side and the base member at its normally upper side mattress portions, said back member having at its normally forward side a mattress portion, all of said mattress portions cooperating for forming a complete mattress when the structure 90 is converted into a bed, and a relatively heavy flap secured to the normally upper edge of the back member adapted to be folded over the mattress portion of the back member when the latter is in a back supporting position, means adjacent the pivot axis of the back member for securing the free edge of said flap to said back member.

2. In an article of furniture of the class 100 wherein a seat member and a back member are hinged to opposite sides of a base member so as to form a chair when folded and a bed when extended, the combination with said seat and back members, of a pair of arm rests extending upwardly from the sides of said seat member disposed with their rear ends abutting the side marginal portions of said back member, wings arranged along the side margins of said back member their lower ends arranged to abut the upper portions of said 105 arm rests, keepers set within said arm rests at the portions thereof covered by said wings, and downwardly directed catches disposed within said wings arranged to engage said keepers.

3. In an article of furniture of the class 110 wherein a seat member and a back member are hinged to opposite sides of a base member so as to form a chair when folded and a bed when extended, the combination 115 with said seat and back members, of a pair of arm rests extending upwardly from the sides of said seat member disposed with their rear ends abutting the side marginal portions of said back member, wings arranged along the side margins of said back member their lower ends arranged to abut the upper portions of said arm rests, keepers set within said arm rests at the portions thereof covered by said wings, and downwardly direct- 120

125
130

ed catches disposed within said wings arranged to engage said keepers, said back member including a pair of frame pieces along each margin each pair defining a channel, a folding leg pivotally mounted in each channel near the extended end of said back member, and a lineally disposed operating means therefor extending along said channel and connected to said base member.

10 In testimony whereof, I have hereunto set my hand at San Diego, California, this 2nd day of January, 1930.

MAX ADLER.
